UNITED STATES PATENT OFFICE.

DAVID A. EBINGER, OF COLUMBUS, OHIO.

WALL-URINAL.

No. 921,096.

Specification of Letters Patent.

Patented May 11, 1909.

Application filed October 17, 1908. Serial No. 458,164.

To all whom it may concern:

Be it known that I, DAVID A. EBINGER, a citizen of the United States, residing at Columbus, in the county of Franklin and State 5 of Ohio, have invented certain new and useful Improvements in Wall-Urinals, of which the following is a specification.

My invention relates to the improvement of wall urinals of that class in which a plural- 10 ity of vertically arranged open compartments or stalls are employed adjacent to a wall and the objects of my invention are to provide a simple and durable wall urinal of this class of improved construction; to pro- 15 vide improved means for maintaining the compartments in a sanitary condition and for ventilating the same and to produce other improvements the details of which will be more fully pointed out hereinafter. These 20 objects I accomplish in the manner illustrated in the accompanying drawing, in which:

Figure 1 is a front elevation of a four-section or compartment urinal of my improved 25 construction showing a portion of the ventilating hood and a portion of the waste trough in section for the sake of clearness in illustration, Fig. 2 is a transverse section on line $x-x$ of Fig. 1, and, Fig. 3 is an en- 30 larged vertical section on line $y-y$ of Fig. 1.

Similar numerals refer to similar parts throughout the several views.

In carrying out my invention, I arrange vertically in front of a wall 1 the desired 35 number of urinal backs or plates 2, each of the latter, which is preferably formed of metal, consisting of a vertical plate, the upper and lower end and side portions of which are curved outwardly imparting thereto an 40 elongated dish or bowl form. With the rear side of each of the back sections 2, I form upper and lower lugs 2^a which are bolted or otherwise secured to angular brackets 3 which project from the face of the wall 1.

As shown more clearly in Fig. 2 of the drawing, the outturned vertical edges of the adjoining back sections 2 embrace opposite sides of the inner edge portions of vertical 45 partition or compartment separating walls or plates 4, the latter being firmly secured in connection with said urinal backs and extending outward to form extensions of the sides thereof. At each end of the urinal body, I 50 employ in place of the separating walls or plates 4, end walls or plates 5, to which the

outer edges of the outer urinal backs are secured and which extend to the wall 1.

In the floor of the room in which the urinals are located and which is indicated at 6, I sink an inclined trough 7 which runs, as 60 shown, beneath the lower ends of the compartments and the lower end of which is provided with a trap or pipe outlet 8 leading to a sewer connection.

9 represents a glass floor plate which is let 65 into the upper surface of the floor 6 until flush therewith and which extends outward the desired distance from the trough 7 toward which said plate inclines slightly.

Supported horizontally above the series of 70 compartments is a water pipe 10 and leading therefrom through the upper outturned portion of each of the back plates 2, is a short pipe arm or nozzle 11 which is closed at its lower end, but which is provided above its 75 end closure on its rear side, with a horizontal recess or opening 11^a.

Above the compartments and above the pipe 10, I provide a suitable form of forwardly inclined hood 12, the upper and rear 80 portion of which is suitably secured to the wall 1, said hood being, as shown, provided with vertical end plates 12^a. Within the wall with which my improved urinal is connected, I provide a vertical flue which is 85 shown at 13 and leading through the inner portion of the wall into this flue, are upper and lower ports or passages 14. The pipe 10, as will be understood, leads from a suitable source of continuous water supply, with 90 the result that water is constantly discharged from the slotted openings 11^a of the pipe arms 11 against the upper portions of the urinal backs 2, thereby providing a constant flow of water against the front surface 95 of said backs which escapes into the outlet trough 7 and which as will be understood, will tend to keep the backs properly cleaned.

By the employment of the glass floor plate 9, it is obvious that injury or discoloration of 100 the floor adjacent to the compartments will be prevented and that the glass may be readily cleaned.

Owing to the natural draft of the flue 13, it is obvious that odors or gases arising from 105 the trough 7, will be drawn through the outlets 14 and into said flue and thence outward to the atmosphere.

It will be observed that the construction of 110 my device is simple although substantial and

that means are provided for maintaining the improved urinal in a sanitary condition.

What I claim is:

1. In a device of the character described, the combination with a building wall having a flue therein, a plurality of concave back members supported adjacent said wall, but spaced therefrom, a hood overhanging all of said back members, water pipes discharging 10 against the outer faces of said back members, and an inclined trough extending below said back members, there being ports formed through the wall adjacent the trough and there being ports formed through said wall 15 between the flue, said ports opening within the hood.
2. In a wall urinal, the combination with a building wall having a flue therein and openings leading through the wall to said flue, and 20 urinal backs of substantially concave form supported from said wall, of a hood extending above said urinal backs there being openings formed in said wall between said flue and

said hood, means for discharging water against said urinal backs, and an inclined 25 trough below the urinal backs, and there being openings communicating with said flue adjacent said trough.

3. In a wall urinal, the combination with a plurality of back plates supported at a distance from a wall, and vertical partition plates uniting the edges of adjacent urinal backs and forming a forward extension thereof, of an inclined trough below said urinal backs, said trough communicating with the 30 space between the wall and urinal backs, and a flue communicating with the upper portion of the space between the urinal backs and wall.

In testimony whereof I affix my signature 40 in presence of two witnesses.

DAVID A. EBINGER.
